UNITED STATES PATENT OFFICE.

WILLIAM A. ELLIOTT, OF EAST GRAND FORKS, MINNESOTA.

AUTOMATIC FIRE ALARM.

Application filed April 22, 1924. Serial No. 708,262.

The present invention relates to improvements in automatic fire alarms, and more specifically to that type of alarm apparatus embodying in an open circuit, a circuit closing device and an audible or visible signal device, the circuit closing device and signal device being positioned at any suitable place with respect to one another.

The primary object of the invention is to provide an automatic fire alarm of the described character, embodying features whereby a circuit will be completed through the apparatus, as the resultant action of an ejecting explosive force.

Other objects of the invention are to provide a simple and efficient fire alarm whereby the working parts thereof may be enclosed, so as to not be affected by fire, prior to the completing of the electric circuit, and one whereby a combustible fuse for detonating an explosive, carried by the alarm, may run to a point or points where fire is most likely to occur.

Other objects and advantages of the invention will appear in the following detailed description, taken in connection with the accompanying drawing, forming a part of this specification, and in which drawing,

Figure 1 is a longitudinal section taken through an alarm constructed in accordance with my invention, and showing the interior mechanism in a set position.

Figure 2 is a view similar to Figure 1, and showing the interior mechanism in a released or signaling position.

Figure 3 is an enlarged transverse section taken on the line 3—3 of Figure 2.

Figure 4 is an enlarged transverse section taken on the line 4—4 of Figure 2.

Figure 5 is an enlarged fragmentary section taken on the line 5—5 of Figure 1, and

Figure 6 is an enlarged fragmentary section taken on the line 6—6 of Figure 2.

Referring to the drawing in detail, and wherein similar characters designate corresponding parts throughout the several views, the letter A designates an automatic fire alarm, comprising a box or casing B for encasing a circuit closer C and a release device D; the release device D being operable through a combustible element E.

The box or casing B for encasing the mechanism of the alarm, preferably consists of a substantially flat, rectangular shaped

metal box body 10 having a removable metal cover portion 11, for closing the open face thereof. This encasing of the mechanism will, in addition to protecting the mechanism against fire, prior to the completing of the electric circuit, also protect the mechanism from dust and the like, and maintain a dry atmospheric condition within the box. A suitable number of openings 12 are provided in the box body 10 for permitting of electric conducting wires to enter the casing for attachment to the circuit closer C, and a single hole or opening 13 is provided for permitting of the combustible element E to enter the casing for operative engagement with the released device D.

Referring to the circuit closer C, which is adapted for completing a circuit through the signal device 14, the same preferably embodies two spaced apart stationary contacts 15 and 16, which are insulatively mounted on the inner face of the base 17 of the box body 10, by combined fastening elements and binding posts 18. A contact arm 19 is pivotally mounted adjacent one end to the stationary contact 16, by a bolt or rivet 20. A coil spring 21, having one end thereof secured to the base 17, and its other end secured to the contact arm 19, is adapted for throwing the free end of the arm into contacting engagement with stationary contact 15, when the arm is released by the action of the release device D. A switch socket or stop 22 is secured to the contact 15 in order that the arm 19 will be stopped and held in contacting relation with the contact 15.

A connecting strip 23 may be insulatively mounted on the base 17 by means of combined fastening elements and binding posts 24. It can be seen that by so providing the binding posts 18 and 24, that the wires 25, which lead to the signal device 14, and the wires 26, which are in circuit with a source of electric energy 27, may be readily connected to the alarm.

Referring to the release device D, the same consists of an arm 28 pivotally mounted intermediate its ends to the base 17, by means of a bolt or rivet 29, and having provided at one side of the pivot bolt, a projection 30 adapted to releasably engage the free end of the contact arm 19. A combustion cup 31 for holding a small amount of explosive material, is positioned at the opposite side

of the pivot 29, with its open end in abutting relation with a stationary combustion shoulder 32 secured to the base 17. This combustion shoulder is adapted to fully close 5 the open end of the cup 31, and also form a stop for the arm 28 which is normally held in a set position by means of a coil spring 33 which is secured at one end to the cup end of the arm, and has its other end secured to 10 the box body 10. An opening 34 is provided in the cup 31 for permitting of the combustible element E, which is preferably in the form of a combustible fuse 35, to enter the cup and lie in contacting relation with 15 the explosive contained therein.

The fuse 35 which extends exteriorly of the casing B, may be run to any desired point or points where fire is most likely to occur, and if desired, branch fuse lines may 20 be connected with a main fuse line which is in communication with the alarm.

It will therefore be seen, that when the explosive within the combustion cup 31 is exploded by the burning of the fuse 35, that 25 the explosive force which ejects from the open end of the combustion cup, will act directly upon the combustion shoulder 32, and by forcing the arm 28 against the action of the spring 33, will cause the contact arm 19 to be released and move to circuit completing relation with the stationary contact 15.

By so enclosing the explosive within a metal casing, it will be maintained in an 30 effective condition against dampness or the like, which might tend to interfere with the successful operation of the alarm. It will also be seen that the combustion cup 31 may be readily refilled and the alarm reset, by 35 merely drawing the arm 28 in a direction against the action of the spring 33.

It is to be understood that minor changes in construction may be made, and that the apparatus may embody a plurality of alarm 40 devices and signal devices, connected in a

suitable circuit, without departing from the spirit or scope of my invention; but,

I claim:—

1. An automatic fire alarm comprising a casing, stationary contacts carried by said casing, a contact arm pivotally connected to one of said stationary contacts, means for normally urging the contact arm into engagement with another of said stationary contacts for completing a circuit therebetween, a release device for normally holding the contact arm in an open circuit position comprising an arm pivotally connected to said casing, a combustion cup for holding an explosive, carried by said arm, a combustion shoulder secured to said casing adapted to close the open end of the cup and form a top therefore, and a combustible fuse communicating with the explosive within said cup for discharging the explosive and releasing said contact arm. 60

2. An automatic fire alarm comprising a casing, stationary contacts carried by said casing, a contact arm pivotally connected to one of said stationary contacts, means for normally urging the contact arm into engagement with another of said stationary contacts for completing a circuit therebetween, an arm pivotally connected intermediate its ends to said casing, a projection 70 provided on said arm at one side of its pivotal point for releasably engaging the free end of said contact arm, a combustion cup for holding an explosive, carried by said arm at the opposite side of the pivotal point, 80 a combustion shoulder rigidly secured to said casing and adapted to close the open end of the cup, means for normally urging the combustion cup into engagement with said combustion shoulder and a combustible fuse 85 communicating with the explosive within said cup for discharging the explosive and releasing said contact arm. 90

WILLIAM A. ELLIOTT.
